UNITED STATES PATENT OFFICE.

SAMUEL BUCHSBAUM, OF CHICAGO, ILLINOIS.

BELT-BUCKLE.

1,272,206.

Specification of Letters Patent. Patented July 9, 1918.

Application filed July 28, 1916. Serial No. 111,776.

To all whom it may concern:

Be it known that I, SAMUEL BUCHSBAUM, a citizen of the United States, residing at Chicago, in the county of Cook and State 5 of Illinois, have invented a certain new and useful Improvement in Belt-Buckles, of which the following is a full, clear, concise, and exact description, reference being had to the accompanying drawings, forming a 10 part of this specification.

My invention relates to belts and has for its object the provision of an improved belt buckle structure to facilitate holding the belt in any given position without the use 15 of holes in the belt proper. More particularly my invention provides a clamping mechanism adapted to engage the free belt extremity at any desired point and hold it firmly. The structure of my invention is of 20 peculiar utility in this connection in that it has structural provision for securely clamping the belt extremity, and at the same time permitting an angular irregularity or displacement in the belt extremities without 25 reducing the firmness of the grip upon the free belt extremity.

My invention concerns itself with means whereby the buckle portions may be removably mounted in place on any belt body.

30 I will explain several forms which my invention may take by referring more particularly to the accompanying drawing, in which—

Figure 1 is a front view partly in section 35 of a belt and buckle structure constructed in accordance with my invention;

Fig. 2 is a view partly in section along line $a-a$ of Fig. 1;

Fig. 3 is a view similar to Fig. 2 showing 40 the adaptability of the belt structure when the parts are angularly displaced;

Fig. 4 is a vertical sectional view to illustrate the structures of Figs. 1, 2 and 3, the front or escutcheon plate having been cut 45 away;

Fig. 5 is a view similar to that of Fig. 4 showing a modified form of link;

Fig. 6 shows a link somewhat similar to the link of Fig. 1 arranged however to 50 operate with a button, and

Fig. 7 is a perspective view of the clamping element.

Referring more particularly to Figs. 1, 2, 3 and 4, I show a belt 1 which has the free

attaching tongue 2 and the looped opposite extremity 3. The looped extremity has a slot 4 through which a link 5 can be inserted and then turned at right angles to occupy the position of Fig. 1. The two portions of the loop 3 can then be snapped together by the clasp 6 to hold the link 5 in position. This link 5 forms part of the buckle structure, which buckle has the front or escutcheon plate 7 and the two side walls 8, 8. Between the side walls there is mounted 55 the stud 9, which stud besides the two distance pieces 10, 10 carries a serrated clamping element 11. This serrated clamping element 11 is pivotally mounted upon the stud 9 and also has pivotal engagement with the link 5, the link having projections 12 to pass through holes in the side walls of said clamping element. This bridgelike clamping element is shown more in detail in Fig. 7. The free belt tongue 2 is adapted to pass 60 rearwardly of the front plate 7 and be clamped into position by the clamping element 11 as clearly shown in Figs. 2 and 3. The structure herein permits the link 5, for instance, to occupy a position at an angle to 65 the front plate, as shown more clearly in Fig. 3, without in any way reducing the clamping characteristics of the buckle, there always being pressure due to one flap of the garment against the clamping element 11. 70 Under these circumstances the angular displacement may be considerably larger than 75 shown in Fig. 3 without affecting the clamping qualities of the structure.

In Fig. 5 I show a link 5^a which can be 80 held by the looped portion 3 without the use of the slot 13 shown in Fig. 1. This link 5^a is again pivotally secured to the clamping element 11 which in turn is pivotally mounted on the stud 9 carried by the side 85 walls 8.

In Fig. 6 I have shown a link 5^b similarly held as shown in Fig. 1 but having a central slotted portion 14 so that it may co-operate with a button 15 fastened to the free 100 belt extremity. This button 15 may of course be mounted upon a suitable attaching device 16 adjustably fastened to the belt as may be desired.

From what has been described the nature 105 of my invention will be readily clear to those skilled in the art, as will also its various modifications within the scope of the ap-

pended claim. Having however thus described one form which my invention may take, what I claim as new and desire to secure by Letters Patent is:

5 A belt and belt buckle device of the character described comprising a front plate having two side walls projecting rearwardly thereof, a clamping element arranged between said side walls, means whereby said
10 clamping element is pivotally mounted within said side walls, said clamping element having a pair of separated bridge like serrated engaging surfaces, and a link of substantial length pivotally carried by said
15 clamping element, said clamping element be-

ing adapted to clamp the belt tongue between it and the front plate, the axis of the pivotal mounting of said link and the axis of said pivotally mounted clamping element being normally in a plane substantially 26 parallel to the plane of said front plate, one belt extremity being pivotally associated with the free extremity of said link.

In witness whereof, I hereunto subscribe my name this 30th day of June, A. D., 1916. 25

SAMUEL BUCHSBAUM.

Witnesses:
